Des. 222,809

Patented Jan. 4, 1972

222,809

COMBINED LAMP HOLDER AND REFLECTOR OR SIMILAR ARTICLE

Richard J. Ford, 1710 Allumbaugh,
Boise, Idaho 83704

Filed May 14, 1970, Ser. No. 22,976

Term of patent 14 years

Int. Cl. D26—99

U.S. Cl. D48—4

FIG. 1

FIG. 2

FIG. 1 is an exploded front perspective view of a combined lamp holder and reflector or similar article showing my new design with a lamp in broken lines for illustrative purposes.

FIG. 2 is a rear perspective view thereof.

I claim:

The ornamental design for a combined lamp holder and reflector or similar article, substantially as shown and described.
